FLOOR TOOL OR NOZZLE FOR AIR-METHOD
CLEANERS

Daniel Benson Repleglo, Berkeley, Calif., assignor to Citizens Trust Company, Toledo, Ohio, a corporation of Ohio, as trustee

Original application August 7, 1928, Serial No. 297,969. Divided and this application March 24, 1931, Serial No. 525,008

11 Claims. (Cl. 15—155)

The invention relates to cleaning apparatus of the type known commercially under the registered trade-mark "Air-Way", and more particularly to the floor tools or nozzles of such apparatus.

The present application is a division of my prior application Serial No. 297,969, filed August 7, 1928, now Patent No. 1,912,386, dated June 6, 1933. In order that the features of the present application may be more readily understood in its preferred embodiment, some of the features which are claimed in my prior application will be described, but it will be obvious that the subject matter claimed in the present application is to be considered as capable of independent use.

The present application is also a continuation in part of my prior application Serial No. 15,529, filed March 14, 1925, which application in turn contains subject matter disclosed in my prior applications and patents as follows:

(a) Application Serial No. 101,695, filed June 5, 1916, now Patent No. 1,345,550, granted July 6, 1920.

(b) Application Serial No. 279,467, filed Feb. 26, 1919, now Patent No. 1,533,271, granted Apr. 14, 1925.

(c) Application Serial No. 427,088, filed Nov. 29, 1920, now abandoned.

(d) Application Serial No. 428,159, filed Dec. 3, 30 1920, now abandoned.

(e) Reissue application Serial No. 509,710, filed Oct. 22, 1921, now reissue Patent No. 16,224, granted Dec. 15, 1925.

(f) Application Serial No. 729,418, filed Aug. 1, 35 1924, now Patent No. 1,541,280, granted June 9, 1925.

An important object of the invention is to improve the form and method of manufacture of the floor tool in the interests of efficiency of operation and economy in construction.

The present application relates primarily to the floor tool or nozzle, which is preferably provided with an enlarged interior and a relatively restricted mouth, and hence is particularly adapted to serve as a housing for a revolute brush, which brush and its operating mechanism form no part of the subject matter claimed in the present application.

According to my invention the nozzle may be formed principally from sheet metal, and is provided with downwardly opening pockets in which are retained stroker elements, the tips of which are permanently curved and extend beneath the inner walls of the pockets. The nozzle is also provided with sheet metal sockets secured to the cylindrical surface of the nozzle on opposite sides of the mouth, and having end openings adapted to receive the shanks of supporting end rollers.

In the accompanying drawings setting forth an illustrative embodiment of the invention, the

nozzle or floor tool is shown provided with a revolving brush, and operating means therefor, in order that the relation between the nozzle and mechanism carried thereby and cooperating therewith may be more readily understood.

In the drawings,

Fig. 1 is a top plan view of a floor sweeper embodying the invention, the floor tool or nozzle of the sweeper being shown as provided with a reversible rotatable brush, operated by an independent source of power, parts of the mechanism being shown in horizontal section so as to show the brush housing, brush-operating means and reversing cams;

Fig. 2 is a view partly in end elevation and partly in vertical section through the brush housing and showing the driving means interposed between the brush motor and the brush;

Fig. 3 is a perspective view on a reduced scale showing a complete portable suction cleaner equipped with the improved floor tool which is provided with the independently driven reversible brush;

Fig. 4 is a top plan view of the floor tool, showing the motor, the spring-supported rollers for the tool, the spring supports for the rollers and the yokes at opposite ends of the tool connecting the roller supports, and furnishing a resilient support for the axis of the rotating brush;

Fig. 5 is a front view of the suction cleaner;

Fig. 6 is a side view of the cleaner, showing, among other features, the floor-engaging means, a tripper for automatically reversing the rotation of the brush, and one of the brush supports and spring stirrups for holding the automatic reversing means out of operation;

Fig. 7 is a detail perspective view showing a pair of rollers, spring supports therefor, the brush-supporting yoke connecting the spring supports, and the stirrups carried by the yoke;

Fig. 8 is a detail view showing one of the floor-engaging strokers or lips of the suction cleaner;

Fig. 9 is an end view showing a metal cap mounted on the end of the brush housing, having a slot to permit removal of the brush, and having slides on the outer face of the cap adapted to receive a reaction plate which coacts with a reversing cam on the end of the shaft of the brush;

Fig. 10 is a vertical section of said end cap, said section passing through the slot of the cap;

Fig. 11 is a view partly in elevation and partly in section showing the brush, the driving connections therefor, the floor-engaging trippers and the reversing cam;

Fig. 12 is an elevation showing the tripper removed from the shaft of the brush;

Fig. 13 is an end view of one of the fixed reaction members which coact with the tripper cams to produce reversal of the brush;

Figs. 14 and 15 are central vertical sections of the reaction plate shown in Fig. 13, but looking in opposite directions;

Figs. 16 and 17 are central horizontal sections 5 of the reaction plate shown in Fig. 13, but looking in opposite directions;

Fig. 18 is a detail elevation showing one of the shields, ferrules or dust caps mounted on the shaft of the brush at the end of the brush 10 housing;

Fig. 19 is an end view showing the rollers, spring supports, brush-supporting yoke and stirrups, and showing in dotted lines the reversing 15 tripper held in inoperative position by one of the stirrups;

Fig. 20 is a fragmentary plan view showing a portion of the brush housing with the motor removed to show the means for adjustably mounting the motor;

20 Fig. 21 is a section on the line 21—21 of Fig. 20;

Fig. 22 is a top plan view of the mechanism for transmitting power from the motor to the brush, such mechanism being capable of producing rotation of the brush in either direction without reversal of the motor;

25 Fig. 23 is a section on the line 23—23 of Fig. 22;

Figs. 24 and 25 are details of a spring washer mounted on the shaft.

Referring to the drawings, there is shown in 30 Fig. 3, an illustrative embodiment of the invention in which a motor for independently operating an automatically reversible brush is applied to a portable pneumatic cleaner of a type similar to that set forth in my Patent No. 1,887,- 35 600, dated November 15, 1932.

In this figure the reference numeral 30 denotes the ordinary fan motor for producing suction in a suction pipe 31, which pipe may be detachably connected to stub handle 32 of a suitable floor 40 tool 33, as by means of the spring connection 34, shown in Figs. 1 and 2.

The floor tool may be mounted upon a plurality of rollers 35, preferably spring-supported, as shown in Fig. 7.

45 One of the important features of the invention included in my Patent No. 1,912,386 consists in providing a motor 36 separate from and independent of the suction-producing motor 30. The motor 36 is connected to operate a revolving brush 37, shown in Fig. 11, by suitable driving connections, such as that shown in detail in Figs. 22 and 23. As shown, the motor 36 is mounted substantially over the center of the cleaner, so that the machine is balanced. A short connection 50 between the motor and the tool is desirable in order that the motor will not interfere with the operation of the device when it is used to clean underneath some low object, as for example, a bureau.

60 The motor 36 may be operated from any convenient source of electrical power, which may be either the same as or different from that operating the fan motor 30. As shown in Fig. 3, the same source of current is employed for both 65 motors, this being supplied by means of a cord 55 which runs down the suction handle 31 and attaches to the fan motor 30. An outlet socket 56 is provided on the fan motor 30 and a socket 57 on the motor 36, permitting a detachable connection between the two motors by means of a cord 58.

70 This arrangement permits the two motors to be operated from a single source of electrical current, and when the floor tool is to be removed 75

from the suction handle, the electrical connection between the two motors 30 and 36 is broken by merely removing one of the plugs attached to the cord 58 from its socket, so that there is no interference with the complete separation of the floor tool from the suction handle.

The shaft 38 of the motor extends through the housing 33 of the floor tool and carries at its lower end a member 39, the inner concave surface of which carries a concave friction lining 40, 10 preferably of leather, which is tightly secured to the member 39 as by gluing. The shape of the inner surface of the member 39 is preferably a segment of a sphere which in plan appears as a circle (see Figs. 22 and 23).

15 The friction surface 40 of the rotating member 39 is adapted to coat with a ring-shaped member 41, the outer surface 42 of which is preferably in the form of a segment of a sphere, so as to smoothly engage the concave spherical surface 40. The ring member 41 is secured to the outside of the hollow brush 37, so that rotation of the ring 41 will also rotate the brush.

20 It will be apparent from a consideration of Figs. 1 and 2 and a comparison of the respective cross sections of the cylindrical housing or nozzle of the cleaner, the roller 37 and the outlet conduit 32, that the cross-sectional area of the outlet conduit is of substantial size as compared 25 with the cross-sectional area of the nozzle, omitting the portion occupied by the brush, being not less than one-half the effective cross-sectional area of the nozzle, whereby free passage of air through the cleaner is made possible, a feature 30 which is particularly desirable in view of the use of end openings in the nozzle which allow a large quantity of air to enter the same. This free passage of air is a characteristic feature of the present device as compared with other devices operating on the principle of obtaining a high degree 35 of vacuum by restricting the openings to the highest possible degree.

40 It will be obvious from an inspection of Figs. 22 and 23 that when the ring member 41 is directly under the center of the friction member 45, there will be no contact and consequently no rotation of the ring member 41 and the brush carried thereby, even when the motor is in operation. When, however, the ring is at one side 45 of the center, the ring 41 will contact with the surface 40, and will be rotated thereby, and its direction will depend on which side of the center 50 the contact is made. It will be seen that by shifting the brush 37 back and forth parallel to its axis, the ring 41 may be moved to one side or the other of the central position, and reversal of the 55 direction of rotation of the brush may be secured. Automatic means for producing such reversal are provided and will be described herein- 60 after.

65 In view of the above-described operation, it will be obvious that it is important to accurately position the motor shaft 38 lengthwise with reference to the brush, and also to accurately determine the height of the friction surface 40. The accurate positioning of the shaft 38 is made possible by providing adjustable means for securing the motor to the housing 33. This is accomplished by providing slots 42, 43 (Fig. 20), 70 elongated in a direction parallel to the brush housing, and by providing extension slots 44, on each side of the aperture 45, through which the motor shaft 38 extends. The motor is secured to the housing by means of screws, one of which 75

is shown at 46 in Fig. 2. Under some circumstances it may be desirable to shift the motor shaft slightly out of the central position, and this is made possible by the elongated slots.

5 In order to adjust the height of the motor to compensate for wear of the friction surface 40 over a period of years, and to insure proper contact with the ring member 41, a plurality of thin washers 47 are provided, which may be removed, 10 one at a time, as it becomes necessary.

While leather is preferred for the surface 40, other friction material may be employed. The ring 41, however, which is mounted on the brush 37, is preferably of metal, and the combination 15 of leather and metal will be found durable and requires no lubrication.

The brush 37 may be of any suitable material, as wood, with suitable tufts or bristles 48 spirally arranged thereon, as shown in Fig. 11. The rotatable brush 37 is provided with a non-rotatable shaft 50 between which and the inner surface of the hollow brush, bearings 51 of impregnated wood or other suitable material are provided. For proper lubrication of the bearings and central shaft, the annular space 52 between the shaft 50 and interior surface of the brush is filled with graphite particles 53, which provide an efficient dry lubrication. Caps 53' are fixed to the shaft 50, near the ends thereof, by means of pins 54, 30 and prevent access of dust and loss of graphite, as well as providing for the proper assembling of the parts of the brush.

The brush is detachably mounted within the housing 33, the ends of the shaft 50 of the brush 33 being supported by removable plates 60, clearly shown in Figs. 1, 2 and 13, which fit in guides 61 carried by caps 62 on the ends of the housing 33, these caps being slotted as at 63 to permit removal of the brush. The plates are reversible 10 and are provided with slots 65, one above and one below a central aperture 64, through which aperture the shaft 50 passes (see Figs. 13-16). The plates are resiliently supported by spring yokes 66 carried by supporting arms 67 upon 15 which are mounted the rollers 35. Each yoke 66 is engaged within the upper groove 65 of the plate 60, and in this manner the cleaner tool is supported in such manner that the brush 37 and the lips or strokers 68 carried by the housing 33 20 are slightly above the surface of the floor when the tool is not in operation, but when pressure is exerted on the tool handle, the roller supports and spring yokes 66 yield sufficiently to permit the strokers 68 and brush 37 to lightly engage 25 the floor.

The roller supports are shown in Fig. 7 and may be of a type such as is set forth in my Patent No. 1,541,280. As shown, spring members 69 are secured to the lower bars of the supports by rivets 70, these spring members being provided with thumb pieces 71 for depressing the springs when inserting them into their sockets 72 (Figs. 4 and 5), or removing them therefrom. Lugs 73 are 65 provided which extend within the sockets and engage notches 74 in the spring members 69 and prevent accidental removal of the roller supports. As shown in Figs. 2, 4 and 5, the sockets for the roller supports are supplied by attaching to the 70 floor tool a hollow sheet member 74a, extending along the front of the tool and by attaching two short hollow members 75 at the rear of the floor tool on each side of the stub handle 32. These sheet metal members may be made at low cost from stock material, which is bent to the required form and the proper lengths cut off. They

are then secured to the floor tool by welding or in any other suitable manner. As shown in Fig. 2, extensions 77 of the sheet hollow metal socket members form, with the tool housing 33, pockets 78 in which are carried the floor engaging strokers or lips 68. The strokers are preferably composed of non-metallic material, as set forth in my application Serial No. 15,529, file March 14, 1925, of which the present application is a continuation in part, and each stroker is provided with a permanently bent or curved tip portion 68a which, when the strokers are in place within the downwardly opening pockets or sockets 78, extend beneath the inner wall 33a of the pocket, which inner wall, as shown in Fig. 2, is an integral portion of the 15 nozzle.

It will be obvious from the above description that the brush 37 may be readily detached from the housing 33 by first withdrawing the roller and yoke units shown in Fig. 7, which permits the end 20 plates 60 to be slid out of the guides 61, carrying with them the shaft 50 carrying brush 37, which shaft is readily withdrawn through slots 63 in end caps 62.

The means for automatically reversing the direction of rotation of the brush 37 in accordance with the direction of movement of the cleaner as a whole over the floor will be described. For producing this result, tripper members 79 are fixedly secured on each end of the shaft 50. These members are adapted to engage the floor at the beginning of each stroke of the cleaner and are provided with arcuate floor-engaging surfaces 80, which are of friction material such as rubber. When the cleaner is not in operation the tripper 35 members are held slightly above the floor, but when pressure is applied to the handle the trippers are brought into contact with the floor and are swung either backward or forward, depending on the direction of movement of the tool. Each 40 of these tripper members is provided with a cam 81, which, when the tripper is rotated in one direction, engages with a complementary cam surface 82, formed on the adjacent reversible reaction plate 60. The effect of this reaction is to move 45 the shaft 50, and with it the brush 37 and ring 41, lengthwise of the axis of the shaft and thus bring the ring 41 into engagement with one side of the friction surface of the rotating clutch member 39, producing rotation of the brush in 50 one direction or the other, depending on the direction in which the tripper is moved by its contact with the surface of the floor.

As previously noted, the reaction plates 60 are reversible. As one part of the cam surface 82 on this plate is high and the other low, it is obvious that by reversing the reaction plates, the direction of lengthwise movement of the shaft in response to rotation of the tripper members 79 may be reversed. Thus it will be possible to have the brush rotate in such direction as to assist the movement of the cleaner as a whole, or by reversing the plates the brush may be caused to automatically rotate in such direction as to oppose the movement of the tool, whether the tool 60 be moved forward or backward over the surface of the floor. In order to make certain that the plates on opposite sides of the brush shaft have their cams set to cooperate with, rather than to oppose each other, the plates are preferably 65 marked with contrasting colors above and below the center of the plate, as for example, red and blue, as shown at 83 and 84 in Fig. 13. Thus, if the same color is above the center on both plates, the operator will know that the cam surfaces are 70 75

so positioned as to cooperate in moving the shaft axially. He will also know that when one predetermined color is up on both plates, the rotation of the brush will always be such as to assist the movement of the cleaner as a whole, and that when the other color is up, the rotation of the brush will oppose the movement of the cleaner. Obviously, any other convenient means of marking the plates other than by contrasting colors 10 may be employed if desired.

It is sometimes necessary to have the brush rotate always in the same direction, regardless of the direction of movement of the cleaner, as for example, when cleaning rugs having the nap running in a single direction. For this reason, means 15 are provided for holding the tripper 79 out of contact with the floor. To this end, a pair of spring stirrups 85 are provided on each of the yokes 66, being positioned at approximately equal 20 distances on each side of the pivot of the trippers 79, as shown most clearly in Fig. 19. By manually raising the tripper on one side or the other of its pivot it may be frictionally engaged with one 25 of the stirrups, and thereby prevented from engaging the floor and from automatically reversing the direction of movement of the brush with each change of direction of movement of the cleaner as a whole.

Obviously by having two stirrups, one on each 30 side of the pivot of the tripper, the brush may be set to rotate constantly either forward or backward, whichever may be desired.

A particular structure has been described with great particularity for the purpose of illustration, 35 but it is obvious that many of the details may be varied without departing from the spirit of the invention.

What I claim is:

1. In a suction cleaner, an elongated nozzle 40 having pockets formed in the front and rear walls of said nozzle and detachable non-metallic lips in said pockets, permanently curved inwardly and forming a relatively restricted mouth portion, said nozzle having an enlarged interior and a 45 cylindrical outlet conduit communicating with said interior and having its axis at right angles to the axis of the nozzle.

2. In a suction cleaner having a suction nozzle provided with an elongated air inlet mouth, pockets formed in the walls of said nozzle, one in front of and one in rear of said inlet mouth, and 50 non-metallic stroker elements detachably mounted in said pockets, each having permanently bent tips extending beneath the walls of said pockets 55 and into the mouth portion of said cleaner.

3. A suction cleaning tool comprising an elongated nozzle having an outlet opening intermediate its ends and an inlet mouth opposite the outlet opening, the nozzle being provided with 60 permanently curved non-metallic lips each having a tip portion extending partially into the mouth of the nozzle, and inner walls integral with the nozzle extending substantially to the tips of the non-metallic lips.

4. In a suction cleaner, an elongated suction nozzle having an enlarged interior and an inlet mouth, a pair of open pockets in the nozzle at the sides of the mouth, and a pair of non-metallic application members, one mounted in 65 each of the pockets, each member having a permanently curved tip portion extending into the mouth.

5. In a suction cleaner, an elongated suction nozzle having an inlet mouth, a pair of open pockets in the nozzle at the sides of the mouth, and a pair of non-metallic application members, one mounted in each of the pockets, each member having a permanently curved tip portion extending into the mouth, one wall of each of said pockets extending to the tip of the corresponding lip member. 5

6. In a suction cleaner, an elongated suction 10 nozzle having an outlet conduit intermediate its ends, adapted for attachment to a suction pipe, an inlet mouth extending lengthwise of the nozzle, a pocket formed in the nozzle adjacent the mouth and opening downwardly, and a non-metallic stroker mounted in the pocket, said pocket having an inner wall extending substantially to the tip of the stroker, and the stroker having a permanently curved tip extending beneath the inner wall of said pocket. 15 20

7. In a suction cleaner, a cylindrical nozzle having a relatively restricted mouth, and longitudinally extending sheet metal sockets secured to the cylindrical surface of the nozzle on opposite sides of said mouth having end openings 25 adapted to receive the shanks of supporting end rollers. 25

8. In a suction cleaner, a cylindrical nozzle having a relatively restricted mouth, and longitudinally extending sheet metal sockets secured 30 to the cylindrical surface of the nozzle on opposite sides of said mouth having end openings adapted to receive the shanks of supporting end rollers, said sockets having extensions spaced from and parallel with the cylindrical nozzle adjacent the mouth thereof, and forming pockets 35 for receiving detachable stroker members.

9. In a suction cleaner, a substantially cylindrical nozzle having a relatively restricted mouth, 40 longitudinally extending sheet metal strips secured to the cylindrical surface of the nozzle on opposite sides of said mouth, said strips having extensions spaced from and parallel with the front and rear walls of the cylindrical nozzle adjacent the mouth thereof, and forming with said 45 wall elongated pockets for receiving detachable stroker members, said stroker elements being detachably retained in said pockets and the nozzle walls extending beyond said strip extensions substantially to the tips of the strokers. 50

10. In a suction cleaner, an elongated suction nozzle having a restricted mouth, a pair of open pockets in the nozzle at the sides of the mouth, and a pair of non-metallic application members, one detachably mounted in each of said pockets, 55 the inner wall of each pocket extending downwardly beyond the outer wall thereof substantially to the tip of the corresponding application member, the tips of said application members being permanently curved and extending beneath 60 said inner walls.

11. In a suction cleaner, an elongated suction nozzle having an inlet mouth, a pair of open pockets in the nozzle at the sides of the mouth, and a pair of non-metallic application members, 65 one mounted in each of the pockets, each member having a permanently curved tip portion, one wall of each of said pockets extending to the tip of the corresponding lip member. 70
